UNITED STATES PATENT OFFICE.

JOSEPH SALOIS, OF LAWRENCE, MASSACHUSETTS.

ADJUSTABLE THIMBLE FOR STOVE-PIPES.

SPECIFICATION forming part of Letters Patent No. 350,322, dated October 5, 1886.

Application filed March 9, 1886. Serial No. 194,656. (No model.)

To all whom it may concern:

Be it known that I, JOSEPH SALOIS, of Lawrence, in the county of Essex and State of Massachusetts, have invented certain new and useful Improvements in Adjustable Thimbles for Stove-Pipes, of which the following is a specification.

My invention is a stove-pipe thimble; and it consists in an improved contrivance where-
10 by such devices are rendered adjustable to suit the height of the pipe or elbow portion of the pipe designed to enter the thimble, all as hereinafter described, and subsequently pointed out in the claims.

15 It not infrequently happens in putting up stoves that the pipe available for use is unsuited in length to enter the thimble in the wall, and there being no means at hand to reconstruct the pipe to meet the exigencies of the case, and no shop or store within ready reach at which new and suitable pipe can be obtained, very considerable inconvenience is experienced, and eventually material expense incurred.

20 25 It is the object of my invention to provide improved means for obviating these difficulties and unnecessary expenses.

In the drawings hereto annexed, and forming a part of this specification, Figure 1 is a front view of my thimble; and Fig. 2 is a vertical section thereof on the line *x x*, Fig. 1, a portion of the wall in which the thimble is fixed being also shown in section in the latter figure.

30 35 Similar letters of reference indicate corresponding parts in both figures.

A represents the frame or body of the thimble, of any suitable length—say, for instance, three feet—and of a width sufficient to have 40 the part containing the pipe-hole supported and adjustably operated therein. This frame is secured in the wall or chimney by being bricked or walled therein, and so far as it extends in the chimney practically forms a part thereof.

45 *a* is the front plate of the thimble, having the pipe-hole *b* formed therein, as shown. This front plate is of considerably greater length than the frame of the thimble, and is constructed as a slide adapted to be moved longitudinally in ways formed in the sides of the

frame. The slide *a* has ratchet-teeth *c* formed in one of its sides adjacent to the frame, and a pawl, *d*, pivoted to the side of the frame, is adapted to engage said ratchet-teeth with its free end, and to be held in engagement therewith by a spring, *e*, also secured to the side of the frame and bearing with its free end on said pawl.

It will be noticed that the frame *A* is fitted 60 in the wall so that its outer face shall be flush, or substantially flush, with the face of the wall or chimney, by which arrangement the plastering and lathing or plastering portion of the wall or chimney is brought between the outer 65 molding, *f*, of the frame and the front face of the slide *a*. It is also to be noticed that the rear surface of the slide is constructed to move in close contact with the adjacent portion *g* of the frame, by all of which means liability of 70 sparks, smoke, or flame from the stove being carried anywhere than directly into the chimney is obviated.

The form of the casing *A* to the rear of the slide *a* is such as to be most suitable to lead 75 into the chimney and to hold the entire contrivance in place therein, and at the same time constitute a perfectly spark and smoke tight conduit between the pipe-hole *b* and the interior of the chimney. I have shown the portion mentioned as provided with a flange, *h*, which serves as a means for holding the frame firmly in position, though it is obvious that the frame might be given a form different from that shown, which would accomplish the same 80 end.

The operation of my invention will now be readily understood. The frame being bricked or otherwise secured in the wall or chimney at the point where the ordinary thimble would have been placed, the slide *a* may be moved up or down therein to bring the pipe-hole *b* to the position it is desired to have it, and there locked by means of the pawl *d*, engaging the ratchet-teeth *c*, as clearly shown in Fig. 1. 95

The design of the front of the contrivance can easily be made such as to constitute an ornamentation, rather than a disfigurement, of the wall, so that no objection on this point can arise.

I do not confine myself or expect to be confined to the precise form and arrangement of

parts shown, as these may be varied without departing from the spirit of the invention. The slide *a* may have more than one hole *b*, as shown, those not in use being closed by removable covers *b'*.

5 5 What I claim is—

1. A stove-pipe thimble comprising a casing formed to act as a spark and smoke tight conduit between the outer surface of the wall 10 or chimney and the interior of the same, said casing being provided with a molding on the front thereof to rest in contact with the face-plastering, and ways in the rear of said molding and face-plastering, and an adjustable slide 15 movable in said ways and provided with a hole for receiving the pipe, as and for the purposes hereinbefore set forth.

2. A stove-pipe thimble comprising a casing formed to act as a spark and smoke tight

conduit between the outer surface of the wall 20 or chimney and the interior of the same, and provided with ways, a plate formed with ratchet-teeth, and a hole for receiving the pipe movable in said ways, and a pawl pivoted to the frame and adapted to engage said ratchet-teeth, as and for the purposes hereinbefore set forth. 25

In testimony whereof I have signed my name to this specification, in the presence of two subscribing witnesses, this 15th day of February, 30 1886.

JOSEPH X SALOIS. [L. S.]
mark.
